UNITED STATES PATENT OFFICE.

FRANÇOIS BORGEL, OF GENEVA, SWITZERLAND.

WATCH-CASE.

SPECIFICATION forming part of Letters Patent No. 478,734, dated July 12, 1892.

Application filed November 18, 1891. Serial No. 412,255. (No model.)

To all whom it may concern:

Be it known that I, FRANÇOIS BORGEL, manufacturer of watch-cases, a citizen of Switzerland, residing at Geneva, Switzerland, 5 have invented an Improvement in Watch-Cases, of which the following is a specification.

Watch-cases have been made with a ring into which the works are inserted, and such ring has been screwed into the watch-case 10 center; but the back in such cases has usually been screwed or sprung upon the watch-case center.

In my present improvements the watch-case is made in substantially one piece—that 15 is to say, the back and center are in one and the edge of the metal at the open side of the case is turned inwardly and screw-threaded and the shank or pendant is permanently fastened to one side of the case, as usual, and 20 the ring that holds the watch-works and face is screwed into the case and the edge of such ring comes into contact with the inner surface of the case-back. In this manner the case is strengthened and stiffened and dust is 25 effectually excluded and the glass is applied at the outer end of the ring that carries the works.

In the drawing I have represented my improvement by a vertical section of the case on 30 an enlarged scale. The case is made with the shank or pendant E at one side of the main case A, which case is composed of a back, center, and inturned flange a at the open side of the case, and this inturned flange is of 35 sufficient thickness for the reception of a screw-thread. The metal ring B is adapted to receive the watch-works and the face, and these works are to be of any desired character, and the ring B should be provided with the 40 offsets of shoulders, as shown in the drawing, for the plates of the watch-movement, and the portion C of the ring is adapted to rest

against the inner surface of the watch-case A at the back thereof, and around the ring B a screw-thread is provided to screw into 45 the screw-thread upon the inturned flange a. The watch-glass G is received into the bezel F, which bezel is advantageously made to snap or spring over the outer edge of the ring C, so that the edge of the bezel passes in between the inner edge of the case at the outer 50 side thereof and said ring C, and the edge of this bezel may be knurled, so that the bezel, the glass, the ring, and the works may be rotated in screwing the ring C into the case or 55 in unscrewing the same, and the parts constructed in this manner are very strong and dust-proof. The winding-stem D' passes through the shank or pendant, as usual, and it is adapted to connect at its inner end with 60 the winding square or arbor D of the watch-works, and the small screw e, passing through the shank into a neck turned in the winding-stem D' is employed to prevent the winding-stem falling out. 65

I claim as my invention—

The watch-case A, having the back rim and inturned flange a in one piece of metal and the surface of the inturned flange screw-threaded, in combination with the ring B, 70 having a screw-threaded exterior to screw into the flange a, the inner edge of the ring B being adapted to set against the inner surface of the case at the back, and a bezel for the glass having a flange that passes in between the case and outer edge of the screw-ring, substantially as set forth. 75

In testimony whereof I have signed my name to this specification in the presence of two subscribing witnesses.

FRANÇOIS BORGEL.
